UNITED STATES PATENT OFFICE.

JAMES H. GERRY, OF NEWARK, NEW JERSEY.

WATCH TRAIN-PLATE.

SPECIFICATION forming part of Letters Patent No. 253,999, dated February, 21, 1882.

Application filed October 28, 1880. (No model.)

To all whom it may concern:

Be it known that I, JAMES H. GERRY, a resident of Newark, in the county of Essex and State of New Jersey, have invented certain new and useful Improvements in Watch-Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to a certain improvement in watch-frames; and it consists in the combination and arrangement of parts, substantially as hereinafter more fully set forth and claimed.

Referring to the accompanying drawings, in which similar letters of reference indicate like parts in each of the several figures, Figure 1 is a plan view; Fig. 2, a section of the same, taken through line *x*; and Fig. 3, a side view of my invention, all of which tend to illustrate the manner of constructing the same.

The mode of constructing my invention is as follows: I strike up or press into shape from a piece of sheet metal, by means of suitable dies, the back train-plate, A, the outer portion or edge thereof being returned so as to constitute a flange, *a*, adapted to engage with the front train-plate, B, in such a manner as to form a sufficient support therefor, as well as to inclose the works thereof, as indicated in Figs. 2 and 3, the edge of the said returned portion or flange being capable, by means of its construction, of being sprung into or on its seat upon the said plate B, as will be readily understood. The said returned portion *a* has a groove running around the interior edge, which engages with a projecting ridge, *b*, formed upon the front train-plate, B. The train-plate A may be cut away, as in Figs. 1 and 3, to give access to the works within.

To prevent the plate A from turning from its proper position and thereby disarranging the bearings of the several wheels therein contained, I form the post *c*, which is fastened into the plate B, as shown. Said post has thereon a shoulder, *d*, upon which the plate A rests. It also projects through said plate A and receives

the bridge or cock *e* and screw *f*, which latter holds the several parts in combination, all of which will be clearly understood by reference to Fig. 2.

I am aware that a cap with its flange let into a groove in the train-plate and secured in position by screws or posts is not new; also, that a ring snapped over the edge of and thus held upon the train-plate to secure it in position without screws or similar fastenings is not new. My invention combines the advantages of both of these, in that its plate forming the top of the cap answers, as in one case, to exclude dust, &c., when the case is open, and as a support for the "cock" or bridge, and to which it may be directly connected, and in that its snap-fastening for securing it to the train-plate serves, as in the other case, to effect the ready or expeditious securing in place and removal of the cap, while at the same time being deprived of the disadvantages of the same of using screws or posts to secure the cap to the train-plate and of exposing the works to dust, &c., when the watch or case thereof is opened for winding or regulating it.

Having thus described my invention, what I claim, and wish to have secured by Letters Patent, is —

1. The combination, with the front train-plate, B, of the back train-plate, A, post *c*, having the shoulder *d* thereon and fastened to said plate B, as shown, the bridge or cock *e*, and screw *f*, all arranged and operating substantially as and for the purpose set forth.

2. The combination of the front train-plate, B, having the undercut shoulder *b*, the back train-plate, A, having a returned portion or flange, *a*, sprung into engagement with the shoulder *b* of plate B, post *c*, having the shoulder *d* thereon and fastened to plate B, as shown, the bridge or cock *e*, and the screw *f*, all constructed substantially as and for the purpose set forth.

In testimony that I claim the foregoing I have hereunto set my hand this 11th day of October, 1880.

JAMES H. GERRY.
